DESIGN FOR AN ARC WELDER

Clifford C. Lee, Aberdeen, S. Dak.

Application May 19, 1938, Serial No. 77,282

Term of patent 7 years

To all whom it may concern:

Be it known that I, Clifford C. Lee, a citizen of the United States, residing at Aberdeen, in the county of Brown and State of South Dakota, have invented a new, original, and ornamental Design for an Arc Welder, of which the following is a specification, reference being had to the accompanying drawing, forming part thereof.

Figure 1 is a perspective view of an arc welder showing my new design.

Figure 2 is a top plan view thereof.

Figure 3 is a bottom plan view.

That side of the arc welder opposite to the side shown in Figure 1 is the same as shown in Figure 1 with the exception that the panels, knob and cord are eliminated.

I claim:—

The ornamental design for an arc welder, as shown and described.

CLIFFORD C. LEE.
